UNITED STATES PATENT OFFICE.

CLEON M. HANNAFORD, OF RICHMOND, VIRGINIA.

LOCK LIFT AND UNCOUPLING ARRANGEMENT USED WITH CAR COUPLINGS.

Application filed October 11, 1921. Serial No. 506,965.

To all whom it may concern:

Be it known that I, CLEON M. HANNAFORD, a citizen of the United States, residing at Richmond, in the county of Henrico and State of Virginia, have invented a certain new and useful Improvement in Lock Lifts and Uncoupling Arrangements Used with Car Couplings, of which the following is a full, clear, and exact description.

This invention is in the nature of an improvement upon the lock lift, otherwise the lock lifter, or top lock lift, and uncoupling arrangement used with automatic couplers on railway cars of the A. R. A. or M. C. B. standard Janney type, and particularly the "type D" coupler, and it is designed to meet the present requirement to dispense with the clevis and link connection between the lift and its operating mechanism and yet provide the flexibility needed in the longitudinal and lateral movements of the coupler, and at the same time minimize alteration of the standard lift operating mechanism, and insure a direct upward lift of the lock lift.

In furtherance of these purposes of the invention, any of the well known and commonly used types of lock lifts may be modified mainly to the extent of somewhat prolonging the head or upper end of the lift and providing it with an eye or hole which may be engaged by an extension of the lift actuating or uncoupling mechanism in the longitudinal line of the coupler, and preferably providing such head with another eye or hole arranged at right angles to the first mentioned eye or hole so as to adapt the lift to those lift actuating mechanisms which run substantially parallel with the end sills throughout, the shank or neck of the head being rounded so that the lift may be inserted and play in the opening of the coupler head in order to insure the necessary flexibility, as I will proceed now to explain and finally claim.

In the accompanying drawings illustrating the invention, in the several figures of which like parts are similarly designated, Figure 1 is a perspective view illustrating the two-hole lift used in connection with a lift actuating mechanism having its connecting element extending substantially in the direction of the length of the coupler. Fig. 2 is a side elevation on a larger scale. Fig. 3 is an edge view of the two-hole lift, and Fig. 4 is

a side view thereof. Fig. 5 is an edge view 55 of the one-hole lift, and Fig. 6 is a side view thereof. Fig. 7 is a front elevation illustrating the invention in connection with a lift actuating or uncoupling mechanism running parallel with the end sill. 60

Referring to Figs. 3 and 4, 1 is a lock lift of approved form, modified to the extent of having its upper portion or head provided with a transverse eye or hole 2, and an adjacent reduced portion formed as a cylindrical or rounded shank or neck 3, above which is the head 4, arranged at right angles to the main body of the lift, and having the hole 5. Such a two-hole lift may be used in connection with either type of lock lift actuating mechanism such as shown respectively in Figs. 1 and 2 on the one hand and Fig. 7 on the other.

Figs. 5 and 6 show a lock lift 6 having the cylindrical or rounded shank or neck 7, and a head 8 provided with a single eye or hole 9. In this instance the head is turned at right angles to the body of the lift for cooperation with a lift actuating mechanism such as shown in Fig. 1. 75

The shank or neck 3 or 7 may have an offset forward or backward to provide for clearance if necessary.

In order to adapt lifts of the character described to couplers and lift actuating 85 mechanism already installed, it is only necessary to discard the clevises, links, chains, pins or cotters now used and to extend the link engaging element 10 of the actuating rod 11 in the direction of the length of the 90 coupler, and such extension need be only great enough to provide for the arc of movement in raising and lowering the lift, that is to say, unlocking and locking the knuckle of the coupler, and in ordinary installations 95 of lift actuating mechanisms there is sufficient metal in the mechanism to permit of its being drawn out to the extent desired, thus avoiding new installations. This actuating or uncoupling rod may be in one 100 piece, as shown in Figs. 1 and 2. In some cases, as indicated in Figs. 1 and 2, it may be necessary or desirable to put a band 12 in the part 10 of the actuating mechanism in order to bring the extension to a level with 105 the head of the lift, but in other instances this bend may be entirely unnecessary.

The upward turn or lip at the end of

the link engaging element 10 can be bent sideways, if desired, for clearance reasons or can be left off entirely in some cases.

5 The actuating rod 11 does not necessarily have to extend out to the center line of the car and then out through the lock lift, but, if desired, for clearance reasons, rod 11 can extend part way along the end sill then have a bend, such as 12, to clear striking 10 castings and then to the center line of the car and then pass through the lock lift on a line with the center line of the coupler or car. The actuating rod is so arranged that its part 10, when the lock-lift is down 15 in place in the coupler, rests on the bottom of the eye or hole in the lock-lift and thus prevents the lock-lift from creeping or working up and out of the coupler.

20 As shown in Fig. 7, the actuating mechanism, which is well known, comprises a lever mechanism 13, pivoted at 14 to the end sill and having an operating handle 15; and in this case also the free end 16 of the lever 13 may be drawn out or extended sufficiently to pass through the 25 transverse hole in the lift, such drawing out being sufficiently extended to permit of the lateral movement of the coupler without disengagement.

30 In all cases the holes or eyes in the lock-lift are large enough to permit freedom 35 of movement without cramping. The eye or hole in the single hole lock-lift and the top hole in the two hole lock-lift are oval, that is to say, deeper than wide, so as to permit the uncoupling rod handle after it has raised the lock-lift, to drop back into approximately a vertical position, thereby eliminating dangerous conditions 40 caused by reducing the clearance between the ends of cars, which is the case with some of the present styles of uncoupling arrangements.

45 By the construction described, all of the requirements of the A. R. A. with respect to the type D coupler are met in a simple and relatively inexpensive way, both for repair and for new work. The invention will permit the railroads to comply with 50 the A. R. A. rule requiring a coupler operating device of a type directly connected to the coupler knuckle locking block lifter, or top lock lift, without the use of clevises, links, chains, pins or cotters, and without 55 incurring the expense of providing special castings and uncoupling arrangements. My device in no way affects the present functions of the type D coupler, but it does provide for a simple and inexpensive uncoupling arrangement consistent with the 60 standard requirements.

65 It will be noted that the eye or hole 5 or 9 is arranged the reverse of the common style of top lock lift, that is, parallel with the center line of the coupler or car or in

the direction of the length of the coupler, and thereby permits a direct upward lift 70 out of the slot in the coupler in an arc of a circle curving toward the car, instead of the customary sidewise lift.

75 Lifts constructed in accordance with this invention may be made so as to fit the openings in the couplers through which their holed heads extend above the couplers. The shape of the hole or slot in the coupler is of no importance since the provision of the rounded shank or neck will go into and operate in any kind of opening in the coupler. The shank or neck may be made square, hexagonal, or of other cross-section 80 in order to adapt it to special forms of coupler openings, but the lock-lift provided with the rounded shank or neck is especially adapted for use in the type D coupler.

85 It will be understood that lock-lifts of the character described are inserted in the couplers from below through openings in the bottoms and their eye-portions pass through the holes or slots in the top wall 90 of the coupler, and in the case of the improved lock-lift of this invention, the lift when its shank is in said hole or slot is then given a turn of ninety degrees so as to bring the hole or eye in the lift in the 95 longitudinal line of the coupler ready to receive the link-actuating mechanism extending out in the same direction.

100 It will be observed that the holes or eyes in the lock-lift and the bearings for the lift-actuating mechanism are sufficiently large to allow enough play and the lift-actuating mechanism itself is so loosely placed in its bearings that compensation is made for both the longitudinal movement of the 105 coupler and its lateral movement.

110 As already stated, the rod 11 may be bent to clear striking castings as well as to adapt it to the eye in the lock lift, and such bending may be as illustrated at 12, or the bend may be similarly or otherwise made elsewhere in the rod to suit the exigencies of installation.

115 The lock-lift and uncoupling arrangement of this invention are not only suitable for freight cars in freight service, but they are also suitable for application to freight express cars which are to be used in passenger service, because the uncoupling rod lays so close to the top of the coupler that the rod 120 would pass under the diaphragm face plate or buffers on passenger cars.

125 Variations in the details of construction are permissible within the principle of the invention and the scope of the claims following.

What I claim is:

130 1. A lock lift for car couplers, adapted for direct engagement with lift actuating mechanism, said lift having its upper portion ex-

- tended and provided with a reduced shank whereby the lift may be turned in the lift opening in the coupler and having a head next thereto provided with an eye or hole 5 to receive and cooperate with the lift actuating mechanism, said eye or hole when the lift is in place in the coupler being located parallel with the center line of the car or coupler.
- 10 2. A lock lift for car couplers, adapted for direct engagement with lift actuating mechanism, said lift having a body of substantially oblong cross-section and provided with a reduced shank and a head arranged 15 at right angles to the body of the lift and provided with an eye or hole to receive and cooperate with the lift actuating mechanism, said eye or hole when the lift is in place in the coupler being located parallel 20 with the center line of the car or coupler.
3. A lock lift for car couplers, adapted for direct engagement with lift actuating mechanism, said lift having a body of substantially oblong cross-section and a head arranged 25 at right angles to the body and provided with a hole or eye located parallel with the center line of the car or coupler and a reduced shank or neck next below the holed head and having a cross-section adapted 30 for cooperation with the shape of the hole in the coupler.
4. A lock lift for car couplers, adapted for direct engagement with lift actuating mechanism, said lift having its head extended and arranged at right angles to the body of the lift and provided with a hole or eye located parallel with the center line of the car or coupler, and a shank or neck next 35 below the holed head and having a cross-
- section adapted for cooperation with the shape of the hole in the coupler, said lift also provided with a transverse hole below said shank or neck and adapted to be located parallel with the end sill or end of the car, either of said holes being capable of use in connection with a lift actuating mechanism without the intervention of clevises and links. 40
5. A lock lift for car couplers, adapted for direct engagement with lift actuating mechanism, said lift having a body of substantially oblong cross-section and a head extended and arranged at right angles to the body of the lift and provided with a hole or eye which when the lift is in place in the coupler is located parallel with the center line of the car or coupler, and a rounded shank or neck next below the holed head. 45
6. A lock lift for car couplers, adapted for direct engagement with lift actuating mechanism, said lift having its head extended and arranged at right angles to the body of the lift and provided with a hole or eye located parallel with the center line of the car or coupler, and a rounded shank or neck next 50 below the holed head, said lift also provided with a transverse hole below said shank or neck and adapted to be located parallel with the end sill or end of the car, either of said holes being capable of use in connection with a lift actuating mechanism without the intervention of clevises and links. 55
- In testimony whereof I have hereunto set my hand this 6th day of October A. D. 1921.
